Primary Examiner — Garth Rademaker*Assistant Examiner* — Llorellys Martinez-Rivera(74) *Attorney, Agent, or Firm* — Craig M. Stainbrook; Stainbrook & Stainbrook, LLP(57) **CLAIM**

The ornamental design for a grow light reflector, as shown and described.

DESCRIPTION

FIG. 1 is a bottom rear right perspective view of a grow light reflector showing our new design;

FIG. 2 is a top front left perspective view thereof;

FIG. 3 is a front elevation view thereof, the rear elevation view being identical thereto;

FIG. 4 is a left side elevation view thereof, the right side view being identical thereto;

FIG. 5 is a bottom plan view thereof;

FIG. 6 is a top plan view thereof;

FIG. 7 is a cross-sectional view thereof, taken along line 7-7 in FIG. 4; and,

FIG. 8 is a cross-sectional view thereof, taken along line 8-8 in FIG. 3.

The broken lines shown in the drawings are included for purposes of illustrating environmental structures only and form no part of the claimed design.
